C. C. HANSEN

PNEUMATIC COAL PICK

Filed Feb. 1, 1923

UNITED STATES PATENT OFFICE.

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY.

PNEUMATIC COAL PICK.

Application filed February 1, 1923. Serial No. 616,309.

To all whom it may concern:

Be it known that I, CHARLES C. HANSEN, a citizen of the United States, and a resident of Easton, county of Northampton, State of Pennsylvania, have invented a certain Pneumatic Coal Pick, of which the following is a specification accompanied by drawings.

This invention relates to coal mining machines and more particularly to a mounting for rock drills which are used as coal picks for undercutting a face of coal and for following coal seams and similar operations in coal mining.

15 The use of coal picks enables the operator to produce a maximum output at a minimum expense. Such machines must be capable of adjustment in various planes, so that the cutting implement may be directed along the coal seams regardless of their pitch. Machines of this type at present in use are usually heavy and comparatively expensive.

The primary object of this invention is to enable a light hand-held pneumatically operated tool of the hammer drill type to be adjustably mounted so that it may be adapted for use as a coal pick in coal mining work. A further object is to construct a mounting for such pneumatic tools which 30 will enable the tool to be adjusted to various positions either in a horizontal plane or a vertical plane or rotated about its longitudinal axis. A still further object is to equip such a standard pneumatic tool with removable guiding means which may be quickly attached to the tool so that it may be used in the mounting.

40 A still further object is to adapt a mounting of this type to accommodate drills provided with either fixed or removable guiding means.

With the above and other objects in view my invention consists in the features of construction and operation set forth in the 45 following specification and illustrated in the accompanying drawings forming a part hereof, in which—

Figure 1 is a side elevation partly in section of a hand-held hammer drill provided with fixed guiding means and mounted in the carriage in operative position, one side of the cradle being removed;

50 Figure 2 is a transverse sectional view taken on the line 2—2 of Figure 1 looking in the direction of the arrows;

Figure 3 is a partial side elevation of one-half of a modified form of cradle having guides adapted to accommodate a rock drill provided with either fixed or removable guiding means, a rock drill with removable 60 guiding means being shown in position within the cradle; and

Figure 4 is a transverse section on the line 4—4 of Figure 3.

Referring further to the drawings, I 65 have shown a non-rotating hammer drill, which may be a standard rock drill, in the cylinder A of which a piston B is adapted to reciprocate, to strike an anvil block B' and thereby actuate the pick C. This hammer drill has a gripping handle A' and is adapted to be mounted on a carriage which includes a cylindrical cradle D, made up of two uniform semi-cylindrical sections E and F, the sections being adapted to be joined by 70 means of bolts G and H, which pass through lugs J and K located on the top and bottom longitudinal edges respectively of the sections E and F. Trunnions L and O are provided at the sides of the sections E and 75 F respectively, and these trunnions L and O are adapted to fit in the hubs P of a pair of wheels Q. The cradle sections E and F have semi-cylindrical internally projecting portions R at either end in which portions 80 85 a semi-circular guiding groove S is formed.

In the preferred modification shown in Figures 1 and 2, the hammer drill is provided with guides adapted to engage the grooves S so that the hammer drill may be 90 rotated about its longitudinal axis when positioned within the cradle. The guides as shown in this instance comprise a pair of integral circular flanges T located at the forward and rearward ends of the cylinder 95 A, but a series of lugs or other guiding means may be provided on the cylinder and used with equal facility. In the present instance, the guide flanges T are formed directly on the outer wall of the cylinder A. 100

In mounting the hammer rock drill in the cradle the guide rings or flanges T are caused to cooperate with the internal circular guiding grooves S located at each end of the cradle and the two cradle sections E 105 and F are bolted together. When thus mounted on the carriage, the cradle and drill may be moved forwardly and rearwardly and may be oscillated in a horizontal plane upon the wheels. The cradle and drill will 110

also be capable of oscillation in a vertical plane upon the trunnions and the drill will also have the capacity of rotation axially within the cradle.

5 The pick C may have a chisel point C' as shown in this instance, but any suitable form of pick may be employed. When a chisel point is used the coal pick C is usually oscillated from side to side so that the cutting edge of the pick describes an arc of a circle in making the cut, and the standard rock drill mounted in the cradle as described herein is readily grasped by its handle A', and manually oscillated or rotated about its longitudinal axis.

Such a machine is especially suited to "one man" operation, being well balanced on the trunnions L and O, so that it is not necessary for the operator to support an excessive weight, regardless of the length of the pick being used. The present machine has a wide range of adjustment and is suitable for use in undercutting or shearing a coal face as well as trimming or brushing

25 down walls of rock or other impurities which may be located along the coal seams.

As shown in Figures 3 and 4 the guide flanges may be in the form of removable ring members made up of two parts U 30 which are adapted to be clamped together about convenient parts of the cylinder of a standard rock drill. These parts U are symmetrical and are internally contoured to accommodate the cylinder or 35 other parts of the rock drill with a relatively close fit. The outer peripheral surfaces V are curved to fit the guiding grooves S and the sides are cut away as seen at W to provide recesses for the ends of the bolts X

40 which securely clamp the two parts U of each removable guide flange together about the rock drill, so that when thus secured about the rock drill the outer periphery of the guide flange is substantially circular 45 except for the breaks at W, so that the guide flange includes practically a series of guiding lugs. The parts U have inner lugs Y provided with holes Z through which the front head bolts a or back head bolts b are 50 passed in assembling the parts U on the rock drill so that the parts U are practically component parts of the rock drill, being secured on the drill by the same bolts a and b which hold other parts of the rock 55 drill together.

The parts U should be so formed that they fit accurately together to form a ring and present a true annular guiding edge, and to insure accuracy of fit the two parts U 60 which are to make up a pair are preferably formed in one piece and split apart along longitudinal lines as seen at c, so that the joint presents a smooth, unbroken surface which moves freely in the guides. The 65 removable guide flanges U are preferably

used on standard rock drills already built, and their location on convenient parts of the rock drill may necessitate the location of the circular guiding grooves of the cradle D in a different position from that shown in Figure 1. The cradle sections are therefore provided with a pair of inner forward and rearward guiding flanges e in addition to the outer flanges f. The cradle illustrated in Figure 3, equipped with two sets of guiding grooves g and h, respectively, will accommodate a rock drill having fixed guiding means, as shown in Figure 1, or removable guiding means as shown in Figures 3 and 4.

These flanges may be in the form of removable rings suitable for attachment to any standard hammer drill. Such removable rings may be constructed so that various sizes of hammer drills will be capable of use in the 85 same cradle, a different set of guiding rings only being necessary to enable any size hammer drill to be adjustably mounted within the cradle.

When the cradle sections E and F are 90 bolted together the rock drill is necessarily enclosed so that the exhaust of motive fluid from the exhaust aperture k takes place within the cradle, and to prevent any obstruction of the exhaust the cradle sections 95 E and F are preferably provided with upwardly directed openings p. The exhaust is thus diffused and muffled, the rock drill and interior of the cradle are kept free of dust and débris and the floor of the mine 100 is not subject to a constant blast of air while the rock drill is in operation, so that the stirring up of dust in the mine or entry is also to a large extent minimized.

I claim:

1. A pneumatic coal pick, comprising a wheeled carriage having a cylindrical cradle trunnioned between the wheels and provided with circular internal guiding means, a fluid actuated rock drill adapted to be enclosed within the cradle, and guides on the cylinder of said rock drill adapted to cooperate with the circular guiding means of the cradle, whereby the rock drill may be moved bodily forward and backward with the carriage and is capable of being rotated about its own longitudinal axis and of being oscillated in vertical and horizontal planes.

2. A pneumatic coal pick comprising a wheeled carriage having a cylindrical cradle trunnioned between the wheels and provided with internal circular guiding means at opposite ends, a fluid actuated rock drill adapted to be enclosed within the cradle and guides on the forward and rearward ends of the cylinder of said rock drill adapted to cooperate with the internal circular guiding means of the cradle, whereby the rock drill may be moved bodily forward and backward with the carriage and is capable

of being rotated about its longitudinal axis and of being oscillated in vertical and horizontal planes.

3. A pneumatic coal pick comprising a wheeled carriage having a longitudinally divided cylindrical cradle and means for securing the portions together, said cradle being trunnioned between the wheels, internal circular guiding means at opposite ends of the cradle, a fluid actuated rock drill adapted to be enclosed within the cradle and guides on the forward and rearward ends of the cylinder of said rock drill adapted to cooperate with the internal circular guiding means of the cradle whereby the rock drill may be moved bodily forward and backward with the carriage, and is capable of being rotated about its longitudinal axis and of being oscillated in vertical and horizontal planes.

4. A pneumatic coal pick comprising a wheeled carriage having a cylindrical cradle trunnioned between the wheels and provided with internal circular guiding means at opposite ends, a fluid actuated rock drill 25 adapted to be enclosed within the cradle, and removable guide rings secured around the forward and rearward ends of the cylinder of said rock drill adapted to cooperate with the internal circular guiding means 30 of the cradle whereby the rock drill may be moved bodily forward and backward with the carriage, and is capable of being rotated about its longitudinal axis and of being oscillated in vertical and horizontal planes.

In testimony whereof I have signed this specification.

CHARLES C. HANSEN.
